(57) **CLAIM**

The ornamental design for a graphic user interface for a cellular phone, as shown and described.

DESCRIPTION

FIG. 1 is a perspective view of a graphic user interface for a cellular phone according to our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of a Graphic User Interface for a Cellular Phone.

The surface(s) or portion(s) of the article not shown in the drawing or described in the specification form(s) no part of the claimed design. The broken line in the drawing is for illustrative purpose only and forms no part of the claimed design.
